CONSTRUCTION OF SUBAQUEOUS
TUNNELS

August Gundersen, Oslo, Norway

Application June 29, 1932, Serial No. 619,980
In Sweden June 26, 1931

6 Claims. (CL. 61—42)

For the construction of subaqueous tunnels one of several methods may be used:

(1) The tunnel may be excavated under the bottom of a river or channel by means of hydraulic shield with or without pressure air. The tunnel section itself is then constructed in iron or concrete.

(2) Embanking of caissons from the surface of the water and subsequent connection of the 10 separate caissons.

(3) A groove or ditch is made in the bottom of the river or channel, the finished tunnel sections of iron or reinforced concrete being embanked in the said groove or ditch, whereby the 15 sections may either be completely enclosed in cast concrete blocks before being embanked in order to counteract the buoyancy, or they may be cast in after having been embanked.

In working according to the last mentioned 20 method the tunnel sections themselves have generally been constructed in iron. The iron tube sections form a carrying construction as well as a scaffolding for the exterior casting of concrete, which is afterwards made with the aid of divers. 25 The interior tunnel section may, however, also be constructed in reinforced concrete, either in the form of tube sections or in other forms.

In accordance with the methods hitherto used 30 no connection has however been obtained between the inner tunnel section and the exterior cast concrete block in such a manner that the exterior mass of concrete is adapted to serve not only as a counter balance against buoyancy but also as a carrying construction by itself.

The object of the present method is to avoid 35 this drawback. The invention particularly relates to tunnels for street traffic, in which it is necessary to use artificial ventilation.

In accordance with the present invention tunnels of this type are composed of tunnel sections 40 having two vertical side walls, the upper and lower edges of which are interconnected by means of horizontal slabs as well as by means of arcs. The horizontal slabs as well as the arcs 45 are reinforced and the space enclosed between them is utilized as ventilation channels etc. for the tunnel.

The reinforcement of the two horizontal slabs 50 is so determined that these slabs besides serving as a support for the road surface and a ceiling respectively also serve as tension members adapted to take up the considerable horizontal stresses transferred from the edges of the vaulted surfaces at the bottom and top of the tunnel.

By further extending the reinforcement of the

horizontal slabs laterally in both directions so that the tension members are securely anchored in the concrete cast about the tunnel sections after the latter have been placed in position, the result is secured that the tension members also serve to take up pressure transferred from the vaulted top and bottom surfaces owing to the exterior concrete casting. In this manner the exterior cast concrete actually does not only serve as a counter weight but also as a carrying element forming a secondary or auxiliary tunnel in case the inner section should in any manner be destroyed or exposed to over stress, in other words a double security is obtained. This point is one of great importance for tunnels the tops 10 of which are close to the bottom of a river or channel or the like trafficked by vessels.

In the drawing
Figure 1 shows a cross sectional view through 20 a tunnel section,

Figure 2 is a horizontal sectional view taken upon the line 2—2 of Figure 1, and

Figure 3 is a vertical sectional view taken on the line 3—3 of Figure 1 looking in the direction of 25 the arrows.

The tunnel section itself comprises the two vertical side walls 1, 2, which are connected with the exterior side walls or scaffolding walls 3, 4 by means of vertical walls or ribs 12 in the form of beams with or without perforated webs. The 30 upper and lower edges of the vertical side walls 1, 2 are interconnected by means of the horizontal surfaces 5, 6 and the arched or vaulted surfaces 7, 8.

The reinforcement of the horizontal slabs or 35 surfaces 5, 6 operates as tension members for the vaulted surfaces 1, 8. Further the reinforcement irons 9 with the disks 11 in the horizontal surfaces 5, 6 may be extended laterally in both directions so as to be securely anchored in the concrete block 10, which is cased about the tunnel section between the scaffolding walls 3, 4 after the tunnel section has been placed in position. In this manner even the concrete cast on the exterior surface of the vaulted surfaces 1, 8 will 45 act as a pressure resisting arch in addition to the carrying arches 7, 8.

The part of the exterior concrete casting utilized in this manner is indicated with dotted 50 lines 14.

In case the tunnel sections are made of iron instead of concrete as specified the horizontal surface-sheets serve as tension members and are laterally extended in the manner specified above 55 for the reinforcement irons.

I claim:

1. A tunnel section for subaqueous tunnels comprising two interior side walls, a flat and a curved wall interconnecting the upper and lower edges of said interior side walls, two exterior side walls located parallel with and spaced from the first named interior side walls, concrete filling the space between said interior and exterior walls and covering said curved walls and members located at substantially the juncture of said interior side walls and said flat and curved walls and extending laterally towards said exterior side walls.
- 5 10 15 20 25
2. A tunnel section for subaqueous tunnels comprising two interior side walls, a flat and a curved wall interconnecting said interior side walls at their upper and lower edges, two exterior side walls located parallel with and spaced from said first named interior side walls, concrete filling the space between said interior and exterior walls and covering said curved walls, members located at substantially the juncture of said interior side walls and said flat and curved walls extending laterally towards said exterior side walls and anchoring means at the free ends of said members for providing a grip in the concrete.
- 30 35
3. A tunnel section for subaqueous tunnels comprising two interior side walls, a flat and a curved wall interconnecting the upper and lower edges of said interior side walls, two exterior side walls located parallel with and spaced from the first named interior side walls, concrete filling the space between said interior and exterior walls and covering said curved walls and members located at substantially the juncture of said interior side walls and said flat and curved walls extending laterally towards said exterior side walls and said members being connected with said exterior side walls.
- 30 35
4. A tunnel section for subaqueous tunnels comprising two interior side walls, top and bottom walls interconnecting the upper and lower edges of said interior side walls, two exterior side walls located parallel with and spaced from said first named interior side walls, concrete filling the space between said interior and exterior walls and covering said top and bottom walls and members located at substantially the juncture of said interior side walls and said top and bottom walls extending laterally towards said exterior side walls.
- 5 10 15 20 25
5. A tunnel section for subaqueous tunnels comprising two interior side walls, top and bottom walls interconnecting the upper and lower edges of said interior side walls, two exterior side walls located parallel with and spaced from said first named interior side walls, concrete filling the space between said interior and exterior walls and covering said top and bottom walls, members located at substantially the juncture of said interior side walls and said top and bottom walls extending laterally towards said exterior side walls and anchoring means at the free ends of said members for providing a grip in the concrete.
- 20 25
6. A tunnel section for subaqueous tunnels comprising two interior side walls, top and bottom walls interconnecting the upper and lower edges of said interior side walls, two exterior side walls located parallel with and spaced from said first named interior side walls, concrete filling the space between said interior and exterior walls and covering said top and bottom walls and members located at substantially the juncture of said interior side walls and said top and bottom walls extending laterally towards said exterior side walls and connected thereto.
- 30 35

AUGUST GUNDERSEN.
